UNITED STATES PATENT OFFICE.

PLATO G. EMERY, OF CHICAGO, ILLINOIS.

SASH-LOCK.

1,032,534.

Specification of Letters Patent. Patented July 16, 1912.

Application filed June 1, 1908. Serial No. 435,868.

To all whom it may concern:

Be it known that I, PLATO G. EMERY, a citizen of the United States, residing at Chicago, in the county of Cook and State of Illinois, have invented new and useful Improvements in Sash-Locks, of which the following is a specification.

It has happened with some frequency that a passenger on a railway train has suffered serious injury by having a window sash fall on his hand or fingers and such accidents not only cause great suffering and sometimes permanent injury to the passenger but they have occasioned considerable loss by damages to the railway companies. It is a fact, also, that some persons have intentionally allowed a window sash to drop on their fingers with the deliberate purpose of collecting damages for the injuries sustained.

It is my object to prevent a window sash from closing in a manner which will produce an accident of this kind and with this end in view I provide for closing the sash by an intermittent or step by step movement so that a passenger cannot, either accidentally or intentionally allow a sash to drop in such manner as to cause him injury.

The invention also has for its object to provide a sash lock which will permit the sash to be locked in any one of a number of predetermined positions and in such a manner that it can not drop to closed position without manual manipulation.

In the drawings Figure 1 is a general view of a window with the sash raised and showing by broken lines the several stopping points or steps of the sash in moving to closed position. Fig. 2 is a vertical sectional view on the line 2—2 of Fig. 3, showing the invention embodied in a metallic frame and sash. Fig. 3 is a transverse sectional view on the line 3—3 of Fig. 2. Fig. 4 is an elevation showing a portion of the anti-rattling device; Fig. 5 shows the anti-rattling device of Fig. 3 arranged in a different position; Fig. 6 shows in transverse section a metal window frame in which one of the stops is made integral with the post; Fig. 7 shows both of the stops made integral with the post; Fig. 8 is a sectional view showing the invention embodied in a different form in a wooden frame and sash; Fig. 9 is a horizontal sectional view on the line 9—9 of Fig. 8; Fig. 10 is a detail front view of the locking bolt operating means

shown in Figs. 8 and 9; Figs. 11, 12 and 13 are views similar to Fig. 3 but showing the invention in different forms; Fig. 14 is a vertical sectional view of a wooden stop; Fig. 15 illustrates another embodiment of the invention; Fig. 16 illustrates a shoulder plate used with the construction of Fig. 15.

In the drawings, 1 is the window sash, and 2 the posts, 3 the stops and 4 the sill of the frame. All these parts may be made of metal, as shown on Sheet 1, or of wood, as shown on Sheet 2, or part of metal and part of wood.

Referring first to the metallic construction (Figs. 1, 3) the stops 3, 3', are preferably made in channel form and fastened to the post 3 in any suitable manner to form the guide groove for the sash. On their inner opposing sides the stops are provided with a plurality of shoulders 5 and between the shoulders the stops are slotted or otherwise constructed to form recesses 6. Any number of shoulders may be provided on the stops but the shoulders on one stop should be arranged out of alignment with or in staggered relation to the shoulders on the other stop. A portion 5' of the metal cut out to form the slot above each shoulder may be bent inwardly to a horizontal position to widen the shoulder if desired. A portion 5'' of the metal cut out to form the slot beneath each shoulder may be bent inwardly into an inclined position to form a guide, if desired. The locking device 7 is arranged within the sash 1 and it has a handle member 8 which projects through an opening 9 in the inner side of the sash (Fig. 3) and a locking bolt 10 formed by two lateral projections 11, 11' which are arranged to operate in openings 12 in the sash. A spring 13 is arranged within the sash to bear on the locking device and push it normally toward the inner side of the sash. The locking bolt is longer than the distance between the two stops of the window frame and the locking device is capable of moving laterally within the sash a sufficient distance to bring one or the other end of the bolt into position for operative engagement with a shoulder on the stops. In the construction illustrated in the drawings the end 11' of the locking bolt will engage a shoulder on the stop 3' when the locking device is pushed forward manually toward the outer side of the sash and against the pressure of spring 13; and when the manual pressure on

the locking device is removed and the spring returns it to normal position, as shown in Fig. 3, the end 11 of the locking bolt will engage a shoulder on the stop 3. Near the 5 lower end of stop 3 I provide one or more openings 14, 15, to receive the end 11 of the locking bolt, and the lower edge 14' of the opening 14 constitutes a shoulder similar to the shoulders 5. The upper edge 15' of 10 opening 15 constitutes a shoulder with which the bolt engages to lock the sash in closed position. The stop 3' has a slot 6 located opposite these openings.

When the sash is closed the end 11 of the 15 bolt will project into the lower opening 15 to lock the sash. To open the window the operating handle is pushed in until the end 11 of the bolt is disengaged from opening 15 and the end 11' of the bolt is projected 20 into the lower recess of the stop 3'. The bolt is held in this position until the sash has been raised sufficiently to carry the bolt above the opening 14 after which the handle may be released and the sash raised to its 25 upper limit of movement. As the sash moves upward above opening 14 the end 11 of the locking bolt will engage each inclined guide 5'' which will force the bolt outward to clear the adjacent shoulder. After passing 30 a shoulder on stop 3 the spring returns the locking bolt to position to clear the next shoulder on stop 3'. Thus the locking bolt moves back and forth to clear the shoulders and the latter permit the sash to be raised 35 without interference.

To lower the sash from the position shown in Fig. 2 the handle is pressed to disengage the bolt from the shoulder 5. If the manual pressure is removed from the handle as soon 40 as the bolt moves with the sash below this shoulder the spring will return the bolt at once to the position shown in Fig. 2 and it will engage the next lower shoulder on stop 3 and its closing movement will be arrested 45 until the handle is again manipulated. If the manual pressure on the handle is not removed as just described the end 11' of the bolt will engage the next lower shoulder on stop 3' to arrest the sash. If 50 the manual pressure on the handle is then removed the spring will return the bolt to normal position, disengaging it from the shoulder of stop 3' and thrusting it out to engage the next lower shoulder on stop 3. 55 The lower shoulders on stop 3 are preferably located close together so that each step in the closing movement of the sash will be short and also to provide for locking the sash in any one of several positions close together. Thus the sash is lowered by an 60 intermittent or step by step movement to closed position, the shoulders on stop 3 controlling this movement when done properly and the shoulders on stop 3' preventing the 65 sash from passing a shoulder on stop 3 with-

out stopping. In this construction the lock will be provided at one side only of the sash, but it may be duplicated at the other side if desired.

I provide an anti-rattling device for holding the sash tightly against one of the stops and also to exclude dirt, etc., as far as possible. I prefer to apply this device on the inner stop 3 and it comprises an angular plate 17 (Fig. 3), of which one member 17' 75 is clamped securely in place between the stop 3 and the post 2 and the other member 17'' is inclined and lies between the stop and the sash 1. The outer edge of the member 17' bears against the sash and pushes it 80 against the stop 3' to make a snug fit and tight joint between the sash and the stop. The member 17'' is provided with slots 18 and shoulders 18' to correspond with the slots 6 and shoulders 5, and with openings 85 19 and shoulders 19' to correspond with the openings 14, 15 and shoulders 14', 15', on the stop 3.

In Fig. 3 the anti-rattling device is shown clamped between the stop 3 and the post 90 2 by the attaching screws 20 but this device may be fastened as shown in Fig. 5. Or the inner shouldered and slotted side of the stop itself may be bent inward to form the anti-rattling means as shown at 21 in Fig. 6. 95 In the latter construction filler blocks 22 are preferably provided within the stop at the screws 20 to support the stop.

In the metallic construction heretofore described the locking bolt operates transversely through the sash and engages shoulders at the sides of the stops. In Figs. 8-10 I have shown another embodiment of my invention in which the locking device comprises a bolt 23 which extends through an 105 opening 24 in the lower part of a wood sash and is somewhat longer than the width of the sash so that its ends will engage shoulders 25 alternating with recesses 26 in the posts at the back of the guide grooves 110 between the stops. A spring 27 is suitably housed within the sash and operates on the bolt to normally project one end thereof into position to engage a shoulder 25 in the right hand post of the frame. In the construction shown in Figs. 8 and 9, means are provided to move the bolt against the pressure of spring 27 to project the other end of the bolt into position to engage a shoulder in the left hand post. This operating 115 means may comprise an angular yoke 28 pivoted at 29 within a chamber 30 in the sash. The yoke engages shoulders 23' on the bolt and it has a handle 31 which projects through a slot 32 in the face plate 33 fastened on the sash over the chamber 30. This face plate has a flange 34 which may be grasped by the operator to facilitate the manipulation of the handle. In this construction the operation is similar to that 120 125 130

previously described but the bolt operates lengthwise of the sash instead of transversely and one set of shoulders is located in one guide groove, at the back thereof, 5 and the other set in the other guide groove, at the back thereof, instead of both sets in the sides of one guide groove.

In Fig. 11 I have shown the locking device of Figs. 2 and 3 in a wood frame.

10 In Fig. 12 the locking device is made in the form of an angle lever 35 pivoted in the sash at 35', one end projecting outward to form a handle 36 and the other end 37 operatively engaged with a slot 37' in the bolt 38. In Fig. 13 the locking device is also made in the form of an angle lever 39 pivoted at 40 in the frame and having on one end an integral bolt 41 curved on the arc of a circle. In the constructions of Figs. 12 15 and 13 the springs 42 and 43 are located on the inner side of the locking device to hold the handles in more convenient position, in these particular constructions, for operation, and of course the shoulders would be 20 reversed so that those on the outer stop of Fig. 2 would be located on the inner stop. In this connection it may be said as to all the constructions that the same reversal of position is possible if the locking device 25 is set accordingly.

In Fig. 14 I have shown part of a wood stop 44 for use with the locking devices of Figs. 11-13, the shoulders 45 being formed between the recesses 46.

30 My invention may be embodied with a window frame of common construction comprising a wood post 47 and stops 48 (Fig. 15) without changing the form of the stops or the posts to provide the shoulders and recesses heretofore described, as illustrated in Figs. 8 and 9. In this adaptation of the invention the shoulders 49 are formed on plates 50 which are fastened to the stops as shown in Fig. 15. These shoulders 49 correspond, to all intents and purposes, with the shoulders heretofore described and the space between each pair of shoulders on each stop constitutes the recesses which correspond to the recesses heretofore described. 35 The locking device 51 may be of any of the forms heretofore described and it is located so that the bolt 52 is arranged in operative relation to the shoulders 49.

It will be readily understood by those 40 skilled in the art that the invention can be embodied in a window sash and frame in various combinations of wood and metal and therefore I do not restrict myself to the particular material of which any of the parts are made. One or both of the stops may be formed integral with the post, whether made of metal or wood, and in Fig. 6 I have shown a stop 53 made integral with the metal post 54, the other stop 55 45 being removable to facilitate the insertion

and removal of the sash. In Fig. 7 I have shown both stops 56 made integral with the metal post 57.

I prefer to employ the spring in connection with the locking device but it may be 70 omitted if desired for the bolt is longer than the distance between the vertical planes of the edges of the shoulders and hence it is in position at all times to engage a shoulder at one or the other end. 75

My invention is simple in construction and inexpensive to make. It can be readily applied to cars now in service by simply changing the stops and locking devices. It compels the lowering of the sash by an intermittent step by step movement and the lower step is short so that no injury will be caused even if the passenger does stick his finger beneath the sash. It is necessary for the passenger to manipulate the locking device to lower the sash from one step to the next and it is this manipulation which protects him against injury. 80 85

I may provide only one opening at the lower end of stop 3 with which the bolt will 90 engage to lock the sash or I may provide a plurality of openings or a plurality of the shoulders 5 to insure a succession of short stops in the movement of the sash to closed position as it nears the sill. As heretofore 95 explained the invention can also be applied to window frames without changing the stops by using the shoulder plates as illustrated in Figs. 15 and 16. The inclined guides beneath the shoulders are provided 100 to enable the sash to be raised, after it is unlocked, without manipulating the locking device as is necessary in closing the sash for, as before explained, the bolt will be operated by engagement with said guides to clear the 105 shoulders on the upward movement of the sash, and these guides may be formed in any suitable manner.

What I claim and desire to secure by Letters Patent is:

1. The combination with a window frame, of a plurality of shoulders arranged thereon in two series, a sash guided in the frame, and a locking bolt movable through the sash and always in position to engage a shoulder 110 in one or the other series to arrest the downward movement of the sash. 115

2. The combination with a window frame, of a plurality of shoulders arranged thereon in two series, the shoulders in one series being staggered with relation to the shoulders in the other series, a sash guided in the frame, and a locking bolt movable through the sash and always in position to engage a shoulder 120 in one or the other series to arrest the downward movement of the sash. 125

3. The combination with a window frame, of a plurality of shoulders arranged thereon in two series, a sash guided in the frame, and a locking bolt movable through the 130

sash transversely from side to side thereof and always in position to engage a shoulder in one or the other series to arrest the downward movement of the sash.

5. The combination with a window frame, of a sash guided in the frame, a locking bolt movable through the sash to arrest the downward movement of the sash, and means on the frame on opposite sides of the sash 10 to be engaged by said bolt and permit the lowering of the sash by an alternating movement.

5. The combination with a window frame, of a plurality of shoulders arranged thereon in two series, a sash guided in the frame between said series of shoulders, and a locking bolt carried by the sash and longer than the distance between the two series of shoulders to engage the same.

20. The combination with a window frame, of a plurality of shoulders arranged thereon in two series, a sash guided in the frame between the series of shoulders, a locking bolt movable through the sash and longer than the distance between the two series of shoulders to engage the same, and a spring acting on said bolt to hold it normally in position to engage a shoulder in one series.

7. The combination with a window frame, 30 of a sash guided in the frame, a plurality of shoulders arranged thereon in two series, the shoulders in one series being in staggered relation to the shoulders in the other series, a locking bolt movable through the sash and longer than the distance between the two series of shoulders to engage the same, and a spring acting on said bolt to thrust the bolt normally into position to engage a shoulder in one series and out of 40 position to engage the shoulders of the other series.

8. The combination with a window frame, of a pair of stops thereon, a plurality of shoulders and recesses alternately arranged 45 in two series in the stops, the shoulders in each series being opposite recesses in the other series, a sash guided in the frame, and a locking bolt movable through the sash and always projected from the sash to enter 50 a recess in position to engage a shoulder in one or the other series to arrest the downward movement of the sash.

9. The combination with a window frame, of a pair of stops thereon, a plurality of 55 alternate shoulders and recesses arranged in two opposite series in said stops, a sash guided in the frame between the stops, and a locking bolt movable through the sash and longer than the distance between the stops 60 to enter a recess and engage a shoulder in one or the other series to arrest the downward movement of the sash.

10. The combination with a window frame, of a pair of stops thereon, a plurality of 65 alternate shoulders and recesses arranged in

two opposite series in said stops, the shoulders in each series being opposite recesses in the other series, a sash guided in the frame between the stops, a locking bolt movable through the sash and longer than the distance between the stops, and a spring acting on said locking bolt to project it from one side of the sash into a recess and in position to engage a shoulder in one of said series. 70

11. The combination with a window frame, of a pair of stops thereon, a plurality of alternate shoulders and elongated recesses arranged in two opposite series in said stops, the shoulders in each series being opposite recesses in the other series, a sash guided in the frame between the stops, and a locking bolt movable through the sash and longer than the distance between the stops to enter a recess and engage a shoulder in 80 one or the other series to arrest the downward movement of the sash. 75

12. The combination with a window frame, of a pair of stops thereon, a plurality of alternate shoulders and elongated recesses arranged in two opposite series in said stops, the shoulders being formed by partitions between the recesses, a sash guided in the frame between the stops, and a locking bolt movable through the sash and longer than the distance between the stops to enter a recess and engage a shoulder in one or the other series to arrest the downward movement of the sash. 90

13. The combination with a window frame, 100 of a pair of stops thereon, a plurality of shoulders and recesses alternately arranged in two opposite series in the stops, an inclined guide beneath each shoulder, a sash guided in the frame between the stops, and a locking bolt movable through the sash and longer than the distance between the stops to engage the shoulders to provide an intermittent downward movement for the sash and to engage said guides on the upward movement of the sash. 105

14. The combination with a window frame, of a pair of hollow metallic stops thereon, a plurality of alternate shoulders and slots arranged in two opposite series in said 115 stops, the shoulders being formed by partitions between the slots and a portion of the metal cut out to form the slot beneath each shoulder being bent inward within the stop, a sash guided in the frame between the stops, and a locking bolt movable through the sash and longer than the distance between the stops to enter a slot and engage a shoulder in one or the other series to arrest the downward movement of the sash. 120

15. The combination with a window frame, of a pair of hollow metallic stops thereon, a plurality of alternate shoulders and slots arranged in two opposite series in said 125 stops, the slots being formed by cutting out

the metal in the stops between the shoulders, a portion of the metal cut out to form the slot above each shoulder being bent inwardly to a horizontal position to widen 5 the shoulder, and a portion of the metal cut out to form the slot beneath each shoulder being bent inwardly into an inclined position to form a guide, a sash guided in the frame between the stops, and a locking bolt movable through the sash and longer 10 than the distance between the stops to enter a slot and engage a shoulder in one or the other series to arrest the downward movement of the sash.

15 16. The combination with a window frame, of a pair of stops thereon, a plurality of

alternate shoulders and recesses arranged in two opposite series in said stops, a sash guided in the frame between the stops, a locking bolt movable through the sash and longer 20 than the distance between the stops to enter a recess and engage a shoulder in one or the other series, a spring to thrust the bolt in one direction into position to engage a shoulder in one series, and a handle connected to the bolt whereby it can be thrust in the other direction into position 25 to engage a shoulder in the other series.
